UNITED STATES PATENT OFFICE.

EDWARD W. SHANNON, OF WATERBURY, CONNECTICUT, ASSIGNOR TO
ROGERS & BROTHER, OF SAME PLACE.

DESIGN FOR A SPOON.

SPECIFICATION forming part of Design No. 21,472, dated April 19, 1892.

Application filed March 22, 1892. Serial No. 426,000. Term of patent 7 years.

To all whom it may concern:

Be it known that I, EDWARD W. SHANNON, of Waterbury, in the county of New Haven and State of Connecticut, have invented a new Design for a Spoon; and I do hereby declare the following, when taken in connection with accompanying drawings and the letters of reference marked thereon, to be a full, clear, and exact description of the same, and which said drawings constitute part of this specification, and represent, in—

Figure 1, a face view of the spoon; Fig. 2, a back view of the same; Fig. 3, a transverse section cutting on line xx of Fig. 1; Fig. 4, a section cutting on line yy of Fig. 1.

This invention relates to a design for the shape of the bowl of a spoon; and it consists in the shape, as hereinafter described, and shown in the accompanying illustrations. The outline of the bowl of the spoon springs either side from the handle, so as to produce at the handle end of the bowl substantially a semi-circular shape; but the curves on each side are continued to a point beyond the general outline of the spoon, and so as to form depressions in the side of the spoon, as at a a . From these points a a the outline curves out-

ward and then contracts to the tip. From the points a , and in lines curving inward and upward toward the handle, as at b b , is the representation of ribs upon the inside of the spoon, as seen in Fig. 1, and the corresponding representation of grooves on the back, as seen in Fig. 2. These shapes are more apparent in transverse section shown in Fig. 3, cutting on line xx of Fig. 1, and also in Fig. 4, cutting on line yy of Fig. 1.

The ornamentation of the bowl of the spoon consists in the representation of the ribs upon the inner surface of the bowl, represented as springing from depressions in the sides of the bowl and curving inward and upward toward the handle, as shown in the illustrations.

I claim—

The design for a spoon, as herein shown and described.

In testimony whereof I have signed this specification in the presence of two subscribing witnesses.

EDWARD W. SHANNON.
